UNITED STATES PATENT OFFICE.

JOSIAH H. SMITH, OF PHILADELPHIA, PENNSYLVANIA, ASSIGNOR TO WILLIAM H. TIGERMAN, OF PHILADELPHIA, PENNSYLVANIA.

SUSPENSION-RAILWAY SWITCH.

1,359,542.

Specification of Letters Patent. Patented Nov. 23, 1920.

Application filed November 29, 1919. Serial No. 341,465.

To all whom it may concern:

Be it known that I, JOSIAH H. SMITH, a citizen of the United States, residing at Philadelphia, in the county of Philadelphia and State of Pennsylvania, have invented certain new and useful Improvements in Suspension-Railway Switches, of which the following is a specification.

My invention relates to improvements in suspension railway switches, the object of the invention being to provide an improved construction of turn table supporting rail sections adapted to be so positioned as to permit a car to move along the main line or follow a turnout or switch.

A further object is to provide a suspension railway with an improved support for a turn table, and suspend from the turn table a frame carrying straight and curved track sections either of which are adapted to be aligned with the rails of the suspension railway structure so as to enable the car to follow a main line or turnout as desired.

A further object is to provide an improved suspension railway switch which is designed for use on monorail systems, and which will most efficiently perform the functions for which it is intended.

With these and other objects in view, the invention consists in certain novel features of construction and combinations and arrangements of parts as will be more fully hereinafter described and pointed out in the claims.

In the accompanying drawings:

Figure 1 is a view in side elevation showing the transverse girders in section.

Fig. 2 is a top plan view.

Fig. 3 is a view in transverse section on the line 3—3 of Fig. 2.

Fig. 4 is a view in horizontal section on the line 4—4 of Fig. 1, omitting the car and its supporting truck.

Fig. 5 is a view in horizontal section through the supporting framework taken along the line 5—5 of Fig. 1, but omitting the moving parts.

Fig. 6 is an enlarged view in section on the line 6—6 of Fig. 2, and

Figs. 7, 8, and 9, are enlarged fragmentary views in section illustrating various details of construction.

1 represents a longitudinal girder, and 2 are transverse girders which are mounted on uprights 3^a and support the longitudinal 55 girder 1.

While it is to be understood that my improved longitudinal girder will be supported by many transverse girders, I have illustrated but two of the latter, and the two 60 illustrated are designed to support my improved switch construction which will be hereinafter described.

The girder 1 is provided with laterally projecting cantalivers 3, supporting a main 65 line rail 4, the latter having a gap therein between the transverse girders 2 as shown clearly in Fig. 4.

5 is a turn out rail which is supported in any approved manner, and between this 70 turnout rail and the rail 4 of the main track, there is also a gap between the girders 2, 2, as shown in Fig. 4.

The girders 2 are connected by short longitudinal girders 6, so that the said girders 75 2 and 6 form a rectangular frame located above the girder 1. The girders 2 and 6 are connected by relatively short bars 7 forming a hexagonal support, and on this hexagonal support a circular track 8 is secured. 80

9 is a turn table composed of channel bars 10 and 11 located at an angle to each other, and at their outer ends connected by an octagonal frame 12, the several members of which are provided with axle stubs 13 85 mounted in wheels 14, the latter supported on the track 8, so that the turn table can readily revolve and be rigidly supported in all positions.

The turn table 9, at its center, supports 90 a depending rectangular frame 15, and said frame is provided at opposite sides with laterally projecting cantalivers 16. One pair of these cantalivers 16 supports a straight rail section 17, while the other pair 95 of cantalivers 16 supports a curved rail section 18. The section 17 is designed to bridge the gap between the sections of main line rail 4, while the curved section 18 is designed to bridge the gap between one section of the 100 main line 4 and the turnout 5, and in order that these rails may properly meet as the turn table is revolved, the ends of all of the rail sections are beveled or curved as shown.

Figs. 2 and 4 illustrate the turn table in a position to connect the main line rail 4 with the turnout 5. The switch rail section 18 is shown in position to connect the ends 5 of these rails.

When it is desired to move along the main track, the turn table is partially revolved to bring the rail section 17 into position to connect the sections 4 of the main line, and it 10 will therefore be noted that the turn table constitutes the carrying means for the switch rails, and while I have illustrated two of these switch rails, it is of course to be understood that the invention is not limited to 15 any particular number.

When the track section is in position, either for the main line or the turnout, the wheels 19 of the truck 20 can run on the rail sections, and while of course the invention 20 is not limited to any particular construction of truck, I have illustrated the same with a hanger 21 supporting the car 22.

I would have it understood that I do not limit myself to the precise construction or 25 shape of the various frames and turn table construction, and various slight changes might be made in the general form and arrangement of parts described without departing from my invention, and hence I 30 do not limit myself to the precise details set forth, but consider myself at liberty to make such changes and alterations as fairly fall within the spirit and scope of the appended claims.

Having thus described my invention, 35 what I claim as new and desire to secure by Letters Patent is:

1. In a suspension railway, the combination with an overhead structure including 40 transversely extending girders and a longitudinal girder secured to said transverse girders and depending below the same; main rails secured to said longitudinal girder and being discontinued between said 45 transverse girders; a turnout rail having an end located adjacent the interruption of said main rail; and means rotatably supported between said transverse girders and having a portion depending below said transverse 50 girders said means supporting a turnout rail section and a main line rail section adapted, due to the rotation of said means, to be moved respectively into alignment with one 55 end of the main line rail sections and the turnout rail and the interrupted portions of the main rail; substantially as described.

2. In a suspension railway, the combination with an overhead supporting structure; rails supported by said overhead supporting structure and having a gap therein; a 60 turntable rotatably mounted on said supporting structure; a frame depending therefrom and having projecting cantalivers; and a rail section supported on said cantalivers and spaced from said frame whereby 65

upon rotation of said turntable the rail section will be turned into position to free said gap; substantially as described.

3. In a suspension railway, the combination with a longitudinal girder and transverse girders, of rails supported by the longitudinal girder having a gap therein between the transverse girders, a frame rigidly secured to the transverse girders, a turn table mounted on the frame, and a rail section secured to the turn table, substantially as described. 70 75

4. In a suspension railway, the combination with a longitudinal girder and transverse girders, of rails supported by the longitudinal girder having a gap therein between the transverse girders, a frame rigidly secured to the transverse girders, a turn table mounted on the frame, a depending frame on the turn table, and a rail section 80 secured to the frame, substantially as described. 85

5. In a suspension railway, the combination with a longitudinal girder and transverse girders, of rails supported by the longitudinal girder having a gap therein between the transverse girders, a frame rigidly secured to the transverse girders, a turn table mounted on the frame, a turnout, and rail sections secured to the frame 90 and adapted to connect the main line sections or one of the latter with the turnout, 95 substantially as described.

6. In a suspension railway, the combination with main line sections and a turnout, 100 of a stationary frame having a circular track thereon above the rail sections, a turn table, stubs projecting from the turn table, wheels on the stubs mounted on the circular track, and switch rail sections connected to 105 the turn table, substantially as described.

7. In a suspension railway, the combination with main line sections and a turnout, 110 of a stationary frame having a circular track thereon above the rail sections, a turn table, stubs projecting from the turn table, wheels on the stubs mounted on the circular track, 115 a frame depending from the turn table, and switch rail sections secured to the frame, substantially as described.

8. In a suspension railway, the combination with main line sections and a turnout, 120 of a stationary frame having a circular track thereon above the rail sections, a turn table, stubs projecting from the turn table, wheels on the stubs mounted on the circular track, a rectangular frame depending from the turn table, and switch rail sections at opposite sides of the rectangular frame, substantially as described. 125

9. In a suspension railway, the combination with main line sections and a turnout, 130 of a stationary frame having a circular track thereon above the rail sections, a turn table, stubs projecting from the turn table,

wheels on the stubs mounted on the circular track, a rectangular frame depending from the turn table, cantalivers projecting from opposite sides of the rectangular frame at 5 its lower end, and switch rail sections supported by the outer ends of the cantalivers, substantially as described.

In testimony whereof I have signed my name to this specification in the presence of two subscribing witnesses.

JOSIAH H. SMITH.
